UNITED STATES PATENT OFFICE.

HARVEY S. RORICK, OF DETROIT, MICHIGAN.

SHADE AND CURTAIN SUPPORT.

1,275,475.

Specification of Letters Patent. Patented Aug. 13, 1918.

Application filed October 9, 1916. Serial No. 124,538.

To all whom it may concern:

Be it known that I, HARVEY S. RORICK, a citizen of the United States, residing at Detroit, in the county of Wayne and State 5 of Michigan, have invented new and useful Improvements in Shade and Curtain Supports, of which the following is a specification.

This invention relates to a combined shade 10 and curtain support and the object of the invention is to provide a simple, attractive and efficient device for holding a shade, a curtain rod and if necessary a supplemental rod for draperies. The device is so constructed as to be easily placed and removed 15 without the use of nails or screws or without marring the woodwork of the casing of the door or window in connection with which the device is used. The device furthermore is adjustable to adapt itself for 20 casings of different sizes so that it can be removed from one casing and applied to another casing of different dimensions.

With the foregoing and other objects in 25 view, the invention consists in the novel construction, combination and arrangement of parts constituting the invention, to be hereinafter specifically described and illustrated in the accompanying drawings which 30 form a part hereof wherein is shown the preferred embodiment of the invention, but it is to be understood that changes, variations and modifications can be resorted to which come within the scope of the matter 35 hereinafter claimed.

In the drawings in which similar reference numerals indicate like parts in the different figures,

Figure 1 is a front elevation of a window 40 or door casing showing my improved device in operative connection therewith.

Fig. 2 is an enlarged view of a portion of the casing shown in Fig. 1 with my device in position thereon.

Fig. 3 is a perspective view showing my 45 improved device.

Fig. 4 is a vertical, central, sectional view of the device shown in Fig. 3.

Fig. 5 is a perspective view of the lower 50 end of a device embodying this invention equipped with a shade bracket different shaped from the device shown in Fig. 3, and

Fig. 6 is a rear elevation of the lower portion of the device shown in Figs. 3 55 and 5.

These devices are intended to be applied to casings of doors or windows and are arranged on opposite sides thereof for supporting a shade roller and curtain rods and are therefore supplied in pairs with the 60 gripping or casing-engaging means reversely positioned so as to engage the right and left hand sides of the casings. Furthermore the members of each pair of devices are similar in all respects except that the 65 lower portions thereof are equipped to receive and support the projecting members at the end of a shade roller which are ordinarily provided with a cylindrical pintle at one end and with a flattened member connected with a spring at the other end, so therefore, the shade brackets of opposite members of each pair are properly fashioned to support the two opposing ends of the shade. As the members of each pair are 70 identically similar except with respect to the shade-brackets the following description will be confined to a description of one member as it is thought the understanding of both will then be entirely clear. The device 75 embodies an upper supporting member 1 provided with a horizontal upper portion 2 terminating at its rear end in down-turned teeth 3 constituting means for gripping or engaging the upper face of the 80 casing. From the front end of the portion 2 the member depends and is preferably bent inwardly to approximately fit the molding 4 on the front of the casing 5, and lie in substantial contact therewith. The lower 85 portion of the member 1 is wider than the upper portion and is provided at its side edges with two inturned portions the opposing faces of which are arranged in spaced 90 relation and are also in spaced relation with respect to the main body portion of the member 1, to provide a channel 8 (see Fig. 95 5). The lower portion is provided with a transverse opening 9 to freely receive the threaded shank end of a clamping screw 10 the rear end of which is provided with a squared head 11 which is held from unintentional rotation by engagement with the opposing edges of the indent portions 6. Mounted on the threaded shank 10 is a 105 thumb-nut 12.

Connected with the member 1 is a shade-bracket supporting member comprising an upright bar 13 of suitable width to be received in the channel 8 and provided with a 110

centrally-disposed slot 14 to receive the clamping screw 10. The slot 14 is narrower than the space between the indent portions 16 and also narrower than the lateral width 5 of the nut 11, so that when the thumb screw 12 is tightened on the screw 10 it clamps the member 13 against the member 1, to prevent vertical movement of the former. Below the slot 14, the member 13 is outwardly bent 10 at 15 to provide a groove to receive the usual beading 16 commonly employed in casings. Below the outwardly bent portion 15 is a depending portion 17 practically in the same vertical plane as the main portion 13. 15 This portion is provided with an opening 18 to receive a clamping screw 19 provided with a thumb nut 20. Coacting with the portion 17 is an L-shaped cross bar 21 having the end 22 thereof bent at right angles 20 thereto and provided with teeth 23 constituting gripping means for engaging the side face of the casing. The member 21 is provided with a longitudinally-extending slot 24 the side edges of which are inclined 25 inwardly toward each other to constitute a seat for the head 25 of the clamping screw 19 which is preferably made square to prevent its unintentional rotation.

The side edge of the portion 17 is disposed at right angles to the main portion to constitute a supporting bracket 26 for supporting a shade-roller and the bracket on one member of each pair of these devices will be provided with a slot 27 and the companion member of the pair will be provided with a cylindrical aperture 28 constituting a bearing, otherwise the members of each pair are identical.

40 The device for supporting curtains and drapery rods comprises an L-shaped bracket consisting of a single flat bar bent so that the two portions thereof are at right angles to each other, one of the portions being denominated by the reference numeral 30 and the other member by the reference numeral 31. The portion 30 is provided with an opening to receive the clamping screw 10 and the portion 31 is provided with a threaded opening to receive a clamping screw 32. Mounted on the portion 31 is a curtain rod support comprising a flat bar 33 provided with a slot 34 to receive the screw 32 and provided with a U-shaped terminus 35 to support the curtain rod. In cases where it is desired to hang two sets of curtains or support two curtain rods there is provided an auxiliary rod support comprising a flat bar 36 having a longitudinal slot 37 to receive the screw 32 and with a 45 U-shaped terminus 38. It is contemplated that the bar 36 will be considerably longer than the bar 33 and in order to support the U-shaped terminus thereof the bar 36 will rest upon the upturned end of the U-shaped 55 terminus 35 of the bar 33.

The device is set up as follows: the various parts are adjusted approximately according to the arrangement shown in Fig. 3 and the upper horizontal portion of the member 1 is seated on the upper face of the 70 casing of a door or window and the points 3 driven into the wood (which is unimportant in view of the fact that this portion is rarely ever finished). The members 13 are then lowered sufficiently to permit the teeth 75 23 to engage the side face of the casing and sustain the device from outward movement. In order to obtain this adjustment the cross bar 21 may be moved transversely of the member 33 after loosening the clamping 80 nuts 20. Of course, the two devices applied to the same casing will be adjusted vertically so that the shade roller will be in a true horizontal plane and the devices the proper distance one from the other to enable the 85 shade rollers to be seated in the two brackets 26. The curtain rods are supported by the U-shaped members 35 and 38 and they may be adjusted toward or away from the window by manipulating the thumb screws 32 90 and which after adjustment are tightened to hold the parts in assembled relation.

I claim,

1. In a device of the class described, a multipart clamping device including an upper vertically disposed clamping member, a right angle bracket vertically secured to the front face of said upper clamping member to have one end extend horizontally outwardly from the casing when in position, a horizontally adjustable curtain pole supporting member having one end formed to receive a curtain pole and having its other end flat and provided with an elongated longitudinal slot, the slotted flat end of the pole supporting member lying against the horizontal end of the angle bracket, and a clamping screw passing through the slot of the pole supporting member and the horizontal end of the angle bracket to secure 100 said member in adjusted positions.

2. In a device of the class described, a multipart clamping device including an upper vertically disposed clamping member, a right angle bracket vertically secured to the 105 front face of said upper clamping member, an outwardly horizontally adjustable curtain pole supporting member attached to said bracket, a second outwardly horizontally adjustable curtain pole supporting 110 member mounted on the first named supporting member, and a single means for uniting both supporting members and the bracket and for securing both of the supporting members in adjusted positions relative to the bracket and relative to each other.

3. A device of the class described including an upper vertical clamping member having its upper end bent to engage over a casing, the other end portion thereof being pro- 115

vided with inturned side edges forming a channel, a lower vertical member having its upper end provided with an elongated longitudinal slot and slidably mounted in said channel, a clamping screw extending through the upper member and the slot of the lower member to secure the lower member in adjusted positions, said lower member having a shade bracket rigid with the lower end 10 thereof, and a cross bar clamping member

transversely adjustably connected with the lower end of said lower member and having one end bent to engage a side of a casing.

In testimony whereof I have hereunto set my hand in presence of two subscribing witnesses. 15
